UNITED STATES PATENT OFFICE.

CHARLES G. BROCKWAY, OF PINE BLUFF, ARKANSAS.

BILLIARD-TABLE RAIL AND CUSHION.

SPECIFICATION forming part of Letters Patent No. 400,032, dated March 19, 1889.

Application filed April 14, 1888. Serial No. 270,715. (No model.)

To all whom it may concern:

Be it known that I, CHARLES G. BROCKWAY, a citizen of the United States, residing at Pine Bluff, in the county of Jefferson, and in the 5 State of Arkansas, have invented a new and useful Improvement in Billiard-Table Rails and Cushions, of which the following is a specification.

My invention relates to certain improvements in that class of billiard-tables in which the rails and cushions are rendered vertically adjustable by means of bolts passing therethrough, and through slots in the bed into nuts adjustable vertically by means of bolts 10 extending up through the bed into contact with the lower sides of the nuts. In this construction the bolts and their nuts move vertically with the rail and cushion, while in my construction, to be presently described, the 15 bolts and their nuts have no vertical movement.

The invention consists in the construction and arrangement of parts, as will be herein-after fully described, and specifically pointed 20 out in the claim.

Figure 1 is a vertical section through the cushion, rail, and part of the bed of an ordinary table, showing the means of securing the rail thereto. Fig. 2 is a similar view showing 25 my improved means of securing the rail adjustably to the bed. Fig. 3 shows the contour of the apertures in the rail and slate bed for the bolt in Fig. 1. Fig. 4 shows the contour of the slot F in the rail.

In all the figures, A represents the rubber cushion; B, the slate top; C, the wooden frame of the table; D, the cushion-rail; G, the cushion-strips, and E the securing-bolt. In Fig. 1 the bolt passes through and closely 30 fits apertures in the rail and slate bed into a nut, n, fixed in the said bed, so that no vertical adjustment of the parts can take place; but in Fig. 2, showing my improvement, the rail D has a vertical slot, F, through which the bolt E 35 passes into an aperture in the slate bed and

into a nut fixed in the bed, just as in the ordinary construction shown in Fig. 1. As shown in Fig. 2, the strip G does not rest on the slate bed when the rail is in its lowered position, for a space is left for ventilation. By 40 loosening or unscrewing the bolt slightly the rail may be moved upward the proper distance without moving the bolt or nut vertically, and then clamped by turning the bolt in a reverse direction. The rail D is held 45 against the edges of the wood frame C and slate bed B, and not above the slate bed with an intervening space by means of spacing-blocks and bolts, as in a prior construction.

I am aware that the rails and cushions at 50 the pockets have been rendered adjustable to lessen the space for the passage of the ball and to adjust these sections properly with relation to the fixed rails and cushions, which were of the ordinary construction.

I am further aware of the construction shown in German Patent No. 3,036, in which the rail and cushion are adjusted vertically by a horizontal bolt and block supported upon the upper end of a vertically-arranged set-screw, and I disclaim such construction.

Having thus described my invention with relation to the prior state of the art, what I claim as new, and desire to secure by Letters Patent, is—

The combination, in a billiard-table, with the bed having a horizontal bolt-hole, and a stationary nut in the bed with its aperture in line with said bolt-hole, of the vertically-adjustable cushion-carrying rail having a transverse vertical slot, and a bolt passing through said slot into the bolt-hole and nut, whereby the said rail may be adjusted vertically without carrying the bolt and nut with it, substantially as set forth.

CHARLES G. BROCKWAY.
